UNITED STATES PATENT OFFICE.

JOHN GOTTL, OF HOVE, BRIGHTON, ENGLAND, ASSIGNOR TO COMMERCIAL CABLE COMPANY, OF NEW YORK, N. Y., A CORPORATION OF NEW YORK.

SYSTEM OF CABLE-WORKING.

1,113,429.

Specification of Letters Patent.

Patented Oct. 13, 1914.

Application filed May 2, 1912. Serial No. 694,750.

To all whom it may concern:

Be it known that I, JOHN GOTTL, a subject of the King of Great Britain, and resident of Hove, Brighton, England, have invented 5 certain new and useful Improvements in Systems of Cable-Working, of which the following is a specification.

In the operation of the ordinary cable recording apparatus the incoming signals 10 are marked on a tape, the character of the signals being determined by their position on one or the other side of the central neutral line. For instance, the dot indications would be marked on one side of the center 15 line and the dash indications would be marked on the opposite side thereof.

In Figure 3 is shown a diagram of an ordinary recorder record. It is to be noted 20 that the dot and dash indications are equal in size and are only distinguished from each other by their positions on opposite sides of the central line. In operating the ordinary and well-known system of cable working a double key is used, the depression of one 25 key sending impulses of current of one polarity to the line for dots and the other key sending impulses of opposite polarity for dashes, the receiving recording instrument being moved by said impulses of current to 30 mark on the recorder slip on one or the other sides of the central line according to the character of the impulses. This system of cable working is defective in that following impulses of current of like polarity are 35 used with the result that the operation of the recorder under the influence of said impulses of like polarity is at times not positive and the signals are consequently not definite and well defined. This system is 40 further defective in that the impulses of current are all of the same strength and the marks indicating the dots and dashes are, therefore, of precisely the same character and differ only in their position on the tape.

45 In my application filed March 18, 1912, Serial No. 684,572 I have described a system of cable working in which each alternate impulse is of opposite polarity, that is to say, each impulse is opposite in polarity to the preceding one, each impulse forming a complete distinct signal unit.

In carrying out the invention described herein I make use of the method of signaling described in my said prior application

and employ in connection with it a double 55 key, one key being employed to send out impulses of current to produce markings corresponding to dots of the ordinary Morse code and the other key to send out impulses to produce markings corresponding to 60 dashes of the ordinary Morse code. Instead, however, of the dot and dash markings appearing on opposite sides of the central line of a recorder record, each following signal is on the opposite side of the said line from 65 the preceding signal without regard to the character of the preceding signal, and the dash markings are distinguished from the dot marks by amplifying or enlarging the dot indications. As set forth in my previous 70 application each signal impulse is opposite in polarity to the preceding one, the reversals in polarity of the line current being controlled by the transmitting apparatus. That principle is made use of in 75 this invention and the double key now so universally used in cable working is employed for the purpose of transmitting impulses of different strength, one key controlling the lighter current and the other the 80 stronger or heavier current and one key being used for dot indications and the other for dash indications, so that the dot and dash indications or marks will be distinguished from each other by their relative 85 lengths instead of by their positions with respect to the central or neutral line.

Another object of this invention is to provide means whereby each signal impulse will be opposite in polarity to the preceding one 90 without regard to which of the keys of the double key is operated, so that if a plurality of impulses are sent out by the dot key, each impulse will be opposite in polarity to the preceding one and the successive dot indications will be on opposite sides of the central line. This same effect will be produced by operating the dot and dash keys alternately, or by operating the dash key to transmit a plurality of impulses to produce dash 95 indications. By this method of cable working the advantages of transmitting signal units by alternate impulses of opposite polarity is made use of and the additional advantage is secured of having one set of signals 100 amplified to distinguish them from the other set of signal indications. It is manifest that this amplification may be made

evident by a written record or marking or by an increase in sound.

In the drawings, Fig. 1 is a diagrammatic view of an apparatus embodying the invention, wherein the discharge from the cable is utilized to effect the reversal in polarity of the line current; Fig. 2 is a similar view wherein a transformer is employed to effect the reversals, the transformer being operated through or with the line charging current; Fig. 3 a diagram showing an ordinary cable recorder record; and Fig. 4 a similar diagram showing a record formed by a recorder operated by this invention.

Referring to Fig. 1 of the drawings, *a* designates the cable; *b* the artificial line; and *c*, *c'* the sending condensers.

d and *d'* represent the sending keys, said keys constituting what I shall term the double key. This key is quite similar to the ordinary double key now so universally used in systems of cable workings. The key *d* is what I shall term the "dot" key, and it is connected by wire *e* to the apex of the duplex bridge of the cable usual in this type of apparatus. The back contact of key *d* is electrically connected to key *d'* by wire *f*. The front contact *h* of key *d* is electrically connected to the vibrating tongue *t* of the polarized relay *r*, said relay being a part of the double polarized relay *R*. The front contact *h'* of the key *d'*, which key I shall term the dash key is electrically connected to the tongue *t'* of the polarized relay *r'*, this latter relay being also a part of the double polarized relay hereinbefore mentioned. The back contact *g* of key *d'* is connected to the polarized relay coils and to earth at *E*, the relay coils being connected together in series. It will thus be seen that when both keys are opened and rest on their back contacts the cable discharge will be through the relay coils to earth. Two batteries may be employed, or one split battery having parts *l* and *l'*, may be used. The front contact *m* of the relay *r'* is connected to the positive side of the full battery and the back contact *m'* is connected to the negative side of the full battery. Both batteries are connected to earth at *E'*. The front contact *n* of the relay *r* is connected to the positive side of the reduced battery and the rear contact *n'* thereof is connected to the negative side of the reduced battery, as shown clearly in Fig. 1.

The operation of the apparatus will be obvious to those skilled in the art but may briefly be described as follows: Upon the depression of the dash key *d'*, with the relay tongues in the position shown in Fig. 1, positive current of the full battery power is sent to the line through the tongue *t'* of the relay *r'*. Upon opening said key the discharge from the cable will pass to earth through the back contact *g* and the coils of

the two relays thereby swinging the tongues of the relays to their back contacts. This will put negative current to the front contacts of the keys and if the dash key *d'* be again depressed, negative current of the full battery will be put to the line, and this operation will be repeated upon each closing of the key *d'*. If, however, the "dot" key be depressed with the relay tongues in the positions shown in Fig. 1, positive current of the reduced battery power will be put to the line. Upon the opening of said key and the discharge of the cable through the relays, the tongues of the relays will be swung against their back contacts, and upon the next depression of the key *d*, negative current of the reduced battery power will be put to the line and so on through each operation of the dot key *d*. The reversals of polarity to the line take place after each operation of each key so that each successive signal is of opposite polarity and each dash signal impulse is amplified or increased over the dot signal impulse. The keys of the double key will, therefore, be operated in the usual manner of double keys of cable operating systems and the duration of the signal or key depression will be the same for both keys, as contradistinguished from the invention described in my prior application mentioned herein, wherein the key depressions are of different durations or periods for the dots and dashes as in the operation of the ordinary Morse key the receiving instrument may be an ordinary Thompson recorder as indicated at *R* in Figs. 1 and 2; or it may be any other form of well-known receiving apparatus responsive to both positive and negative current impulses.

In the arrangement of the apparatus shown in Fig. 2 the back contact *g'* of the dash key *d'* is connected to earth at *E*² instead of being connected to the relay coils as in Fig. 1. The terminals of the relay coils are connected through the secondary winding *S* of a transformer; and the batteries, or the two parts of the split battery are connected to earth at *E*³ through the primary winding *P* of the transformer. The operation of this arrangement of the apparatus is precisely the same as that described with respect to the arrangement shown in Fig. 1 with the exception that the cable discharges to earth at *E*² and the induced currents in the secondary winding of the transformer operate to reverse the tongues of the polarized relays. These induced currents are opposite in character for each charging of the cable, and occur at the opening of the transmitting key. It is, therefore, manifest that as the reversal of polarity of the line current takes place upon the opening of the key it would be impossible to send two successive signal impulses of the same polarity. Should two impulses of

the same polarity be sent to the line it would indicate at once that the apparatus was not in proper working order.

What I claim is:

5 1. The method of telegraphing on submarine lines which consists in transmitting a constantly alternating series of impulses of current, each impulse of current constituting a single unit of a signal, whereby each 10 succeeding signal unit will be formed by a current impulse of changed polarity and no two successive signal units will be formed by impulses of current of the same polarity, the reversals in polarity of the current to 15 the line being controlled by the sending instrument, amplifying some of said signal impulses by an increased current and distinguishing such impulses as signals or units of signals by their strength and irrespective 20 of their polarity.

2. The art of telegraphing which consists in throwing upon the line impulses of successively opposite polarity and varying the strength of such current impulses and distinguishing such impulses as signals or units of signals by their strength and irrespective of their polarity.

3. The art of telegraphing which consists in throwing upon the line impulses of successively opposite polarity and varying the strength of such current impulses and distinguishing such impulses as signals or units of signals by their strength and irrespective of their polarity, and receiving such impulses in accordance with their polarity.

4. A system of electric signaling comprising means for transmitting single signal unit impulses of current, means automatically controlled by said transmitting means for reversing the polarity after each signal impulse, means for varying the strength of said impulses, means for receiving such impulses, said means responding to said impulses in accordance with their polarity and distinguishing them as signals or units of signals by their strength and irrespective of their polarity.

5. A system of electric signaling comprising two transmitting keys, means whereby one key will transmit impulses of current of equal strength, means whereby the other key will transmit impulses of current of greater power than the impulse transmitted by the other key, and means whereby upon the opening of either key the polarity of the current to the line on the next key operation will be reversed.

6. A system of electric signaling comprising two transmitting keys, means whereby one key will transmit impulses of current of equal strength, means whereby the other key will transmit impulses of current of greater power than the impulse transmitted by the other key, and means whereby the discharge

from the cable will reverse the polarity of the line current.

7. A system of electric signaling comprising means for transmitting impulses of current, a polarized relay controlling the polarity of the current impulses transmitted to the line, means whereby when the current to the line is broken by the transmitting means the polarized relay will operate to reverse the current to the line for 70 the next closure of the line current through the transmitting means, means for varying the strength of said impulses, and means for receiving said impulses of current and distinguishing them as signals or units of signals by their strength and irrespective of 75 their polarity.

8. A system of electric signaling comprising two transmitting devices, means whereby one of said devices will transmit 80 impulses of current of uniform strength, means whereby the other transmitting device will transmit impulses of current of uniform strength, these latter impulses being of greater power than the impulses 85 transmitted by the other transmitting device, a polarized relay for reversing the current to the line, and means whereby upon the opening of the line current by either transmitting device the polarity of the current to the line will be reversed for the next 90 operation of either transmitting device.

9. A system of electric signaling comprising two transmitting devices, means whereby one of said devices will transmit 95 impulses of current of uniform strength, means whereby the other transmitting devices will transmit impulses of current of uniform strength, these latter impulses being of greater power than the impulses 100 transmitted by the other transmitting device, a polarized relay for reversing the current to the line, and means whereby upon the opening of the line current by either transmitting device the discharge from the 105 cable will operate the polarized relay to reverse the polarity of the line current for the next operation of either transmitting device.

10. A system of electric signaling comprising means for transmitting impulses of current, a polarized relay controlling the polarity of the current impulses transmitted to the line, means whereby when the current to the line is broken by the transmitting means the discharge from the cable will operate the polarized relay to reverse the current to the line for the next closure of the line current through the transmitting means, means for varying the strength of 115 the said impulses and means for receiving said impulses of current and distinguishing them as signals or units of signals by their strength and irrespective of their polarity.

11. A system of electric signaling com- 120

prising means for transmitting impulses of current, a polarized relay controlling the polarity of the current impulses transmitted to the line, means whereby when the current to the line is broken by the transmitting means the discharge from a suitable capacity will operate the polarized relay to reverse the current to the line for the next closure of the line current through the transmitting means, means for varying the strength of the said impulses and means for receiving said impulses of current and distinguishing them as signals or units of signals by their strength and irrespective of their polarity.

12. A system of electric signaling comprising two transmitting devices, means whereby one of said devices will transmit impulses of current of uniform strength,

means whereby the other transmitting device will transmit impulses of current of uniform strength, these latter impulses being of greater power than the impulses transmitted by the other transmitting device, a polarized relay for reversing the current to the line, and means whereby upon the opening of the line current by either transmitting device the discharge from a suitable capacity will operate the polarized relay to reverse the polarity of the line current for the next operation of either transmitting device.

In testimony whereof I hereunto affix my signature in the presence of two witnesses.

JOHN GOTTF.
